UNITED STATES PATENT OFFICE.

EARLING A. STEINER, OF HILLYARD, WASHINGTON.

RAILWAY-CAR.

1,359,444.

Specification of Letters Patent. Patented Nov. 16, 1920.

Application filed September 30, 1918. Serial No. 256,312.

To all whom it may concern:

Be it known that I, EARLING A. STEINER, a citizen of the United States, residing at Hillyard, in the county of Spokane and 5 State of Washington, have invented certain new and useful Improvements in Railway-Cars, of which the following is a specification.

The present invention relates to improvements in railway cars, of the convertible type, and the invention is specially designed to provide a convertible car that may be used as a refrigerator car, a stock car, a box car, or a coal car and the changes may be made 10 with facility and convenience, thus adapting the car for hauling one commodity to its destination, and on the return haul adapting the car for carrying a different load, as for instance when the car is utilized to carry 15 coal, after being emptied it may be steamed and cleaned and then converted to a refrigerator car for carrying perishable goods.

The invention consists in certain novel combinations and arrangements of parts 25 as hereinafter set forth and claimed, and in the accompanying drawings I have illustrated one complete embodiment of the invention, constructed according to the best mode so far devised for the practical application of the principles of the invention. 30

Figure 1 is a perspective view of a railway car constructed according to the invention the car being shown at one end as a stock or cattle car, and at the other end 35 being adapted for loading freight or merchandise.

Fig. 2 is a sectional view, showing in transverse section, one half of the car, adapted as a refrigerator car, and the other half 40 equipped as a cattle car, the ice box walls being stored out of the way, and the side boards of the car being arranged with the usual spaces between them.

Fig. 3 is a detail view showing rollers 45 and track for the movable bulkheads.

Figs. 4 and 5 are longitudinal sections, at the ends of the car, Fig. 4 showing the ice box to receive ice when converted as a refrigerator car, and Fig. 5 showing the ice 50 wall or bulkhead at the end of the car moved to its extreme position to provide maximum capacity for loading.

Fig. 6 is a longitudinal section of a portion of the car showing the insulation walls 55 of the refrigerator in place, and also show-

ing the suspending or supporting members for the walls when not in use.

Fig. 7 is a detail view of the latch for holding the insulation sections rigid when in operative position.

Fig. 8 is a detail view of one of the holds for the hoisting hooks to lift the insulating wall members, these details being shown in Fig. 6.

Fig. 9, Fig. 10, and Fig. 11 are details of 65 the chain hoist for the ice box walls of the refrigerator and floor or grating, one of these hoists being provided at each end of the car.

Figs. 12 and 13 are a plan and side view 70 showing longitudinally one end of the car to illustrate the top door through which grain, coal, or other similar material may be loaded into the car, and also showing the ice doors for the refrigerator ends of the 75 car.

Figs. 14 and 15 are enlarged detail plan and elevation views showing the running board on the top of the car and the relation thereto of the inlet doors for loading granular material to the car.

The convertible car is designed to comply with the rules of the Master Car Builders and of the Interstate Commerce Commission, and the invention involves the equipment of the usual standard car with the enumerated devices whereby the different ends may be attained to carry out the invention.

The car body, as a whole is designated 90 by the numeral 1, and is provided with the usual vertically hinged doors 2, 2, at the center and opening on both sides of the car, and the floor 3 is of usual and standard construction, as is also the roof 4 of the car.

In converting the car for use as a refrigerator car an ice box 5 is formed at each end of the car, the side walls of the car being made up of insulating boards 6, which extend from the sides of the doorways at 100 the center of the car toward the end ice boxes 5, and these insulating boards are hinged together at 7 to each other, the top board 6' being hinged at 7' to the supporting rail 8 attached to the side of the car. 105 These insulating boards are, of course, to prevent the ingress of heat, so far as possible, to the interior of the car when it is being used as a refrigerator, and when not in use they may be folded to position indi- 110

cated in Fig. 2 where they are shown in vertical parallel position, and suspended from the ceiling 9 of the car on the hooks 10, shown as three in number at each side 5 of the car. The folds of the side insulation members are lifted to position by means of the chain hoist illustrated comprising the chain 11, sprocket wheel 12, winding shaft 13, and hoist chain 14 to which the end 10 hook 15 is attached. A ratchet 16 and pawl 17 are employed to prevent reverse movement of the hoist when not required, and when the pawl is not required it may be turned back to dotted position in Fig. 11. 15 A series of pulleys 18 is provided, spaced at different distances from the longitudinal axis of the car and the chain 11 is used on these selective pulleys in order to locate the hook in vertical position directly over 20 the engaging handles or loops 19 on the folding sections 6, so that the chain 14 and its hook 15 will be lifted in vertical direction to give best results.

In Fig. 7 a detail is shown of the locking bolts 20 forming retainers for holding the foldable sections 6 and 6' in operative position as in Fig. 6, or in folded position 25 in Fig. 3. The bolt 20 is adapted to slide in the housing 21 which is attached to the folding section or board, and the bolt is held by means of the spring 22 in a notch or recess, (not shown) in the vertical rail 23, one of the latter being located at each end of the folding side walls of the car. 30

35 At the ends of the car, bulkheads are provided, indicated as 24, and these bulkheads, which extend transversely of the car and form the fourth side or wall of the ice boxes 5, are each formed with slats 25; that are 40 fixed, and foldable or hinged slats 26 arranged alternately thereof, as indicated at 26' in Figs. 4 and 5. In Fig. 4 the bulkhead is spaced from the end of the car and the slats 26 are turned to open position so that circulation of air may be maintained 45 between the ice box and the interior of the car. The bulkhead also has the usual ventilating slats 27, preferably of metal and the bulkhead also is provided with the usual metal lining or facing for protection of its 50 parts, and the floor of the car, when it is used as a refrigerator car, is provided with gratings 28, preferably in sections so that they may be lifted out of the way through 55 the instrumentality of the chain hoists (Fig. 2) when not needed. When in use however, the floor gratings provide an open-work floor for ventilation and circulation of air for the preservation of otherwise perishable 60 goods.

The bulkheads at the ends of the car for forming the ice boxes are slidable longitudinally of the car, and for this purpose they have suitable hangers to travel in the metallic trackways 29 secured to the side walls of

the car and just beneath the ceiling of the car, there being two trackways for each bulkhead and the bulkhead is suspended between these tracks. Each bulkhead has an upwardly swinging hinged door 30 through 70 which material may be loaded in connection with the door 31 in the end of the car, these doors being utilized when it is required to load materials or freight of a length too great to permit their ingress through the 75 side doors 2, 2. The ice for the ice boxes is passed through the ice doors 32 33, located as usual in the roof of the car near the ends, for cooling the interior of the car and its 80 contents.

When the car is to be converted for use as a cattle or stock car, the bulkheads are moved back to extreme position as in Fig. 5, the floor gratings 28 and the longitudinal, side, folding boards 6 and 6' which form 85 the insulation members for the refrigerator car, are hoisted up beneath the ceiling as in Fig. 2, and then the beveled side boards 25'—26' are arranged as in Fig. 2. These boards 25' and 26' are arranged similar to 90 the boards 25 26 on the bulkheads at the ends of the car, alternate boards being hinged to the fixed boards, and the boards extend from the ends of the car to the center doors at both sides of the car. 95

At the sides and bottom of the car, are provided four longitudinally extending floor strips 34, best shown in Fig. 2. These strips are hinged to the sides of the car and extend from the ends of the car toward the center 100 doors thereof, and when turned up as in Fig. 3 they leave an open space at the floor line through which debris may be pushed when cleaning the car, and thus provide a sanitary arrangement for cleaning the stock 105 car. When used as a freight car, as in Fig. 1, or as a refrigerator car as in Fig. 2, this strip is turned down and under the car side to close the space. When equipped for shipment of cattle or stock, the converted car is 110 well ventilated and open, as indicated at the left end of the car in Fig. 1, and the double thickness of slats or strips 25' 26' render the sides of the car substantially stronger to bear strains from the cattle when pushing against 115 the sides of the car.

In converting the car for a box car, these folding slats 25' 26' are arranged in closed position, at the right in Fig. 1, and then the freight may be loaded through the side 120 doors as usual.

When loading the car with grain or coal, or other granular material, it is desirable that the car be loaded by pouring the material, and for this purpose a door as 35 is arranged near each end of the car, in its roof, the hinged connection being indicated at 36, and a handle or handles indicated at 37, in Figs. 12 to 13. In order to comply with the rules of the Master Car Builders and the re- 125 130

5 requirements of the Interstate Commerce Commission, the running board 38 on the top of the car is provided with staggered joints 39 arranged beyond the ends of these doors 35, so that when the door is opened, the movable section 40 of the board is lifted with the hinged door, and when the door is closed a dangerous joint is eliminated and a smooth and even surface is presented at the 10 joints. To securely hold the doors and movable section of the running board in place, transversely arranged cotter pins or bolts 41 are provided which are passed through aligned perforations in the boards of the 15 running board, as best seen in Fig. 14, and the bolts may be provided with chains 42 fastened to the roof of the car to prevent loss. The usual grain car door, at the interior of the hinged side doors of the car, is 20 provided by the boards 43 that are stowed away in the compartment 44 beneath the car floor (Fig. 2) when not in use, and when grain is to be fed to the car through the doors 35, these grain boards are taken out 25 and placed in proper position in the doorways at the sides of the car.

For disposing of the coal or grain from the car and unloading it with facility, four hoppers 45 are provided, one at each corner 30 of the car floor, and when not in use these hopper openings are closed by the plugs 46 to form a smooth floor surface. When the car is to be loaded with grain or coal, however, these plugs are first removed, and the 35 hoppers are closed by the downwardly swinging, hinged doors 47, one for each hopper, and these are held in place by means of the chains 48 which pass over the pulleys 49 to the winding shafts 50, by 40 means of which the doors are closed. The plugs 46 are stowed away under the roof of the car when not in use.

As before stated, the grain boards to be used at the doors when loading grain or 45 coal, are stored under the floor of the car, the rack floor or auxiliary floor 28 used with the car is adapted for carrying perishable goods is elevated and held suspended in the same manner as the side boards or 50 insulation boards 6 6', these floor gratings and wall members being shown in elevated and stored position in Fig. 3.

A heater door 51 is shown at the right in Fig. 6, and one of these doors is provided at each side of each end of the car, so that 55 the four doors may be utilized for attending to stoves or heaters placed in the four corners of the car when it is desired to heat the car to preserve perishable goods in transit. 60

I claim—

1. The combination in a convertible railway car, of movable bulkheads at the ends of the car having hinged slats to form openings through the bulkheads for circulation 65 of air, means for holding said bulkheads spaced from the car ends to form ice chambers at the car ends, and removable side walls within the car forming insulation members for the compartment between the 70 two bulkheads.

2. The combination in a convertible car of spaced bulkheads, each formed with alternately hinged slats to provide openings through the bulkheads and means for supporting the bulkheads, of hinged, foldable side walls within the car forming insulation members for the compartment between the bulkheads. 75

3. The combination in a railway car having bulkheads spaced from the ends of the car to form ice chambers and said bulkheads having slats arranged to fold alternately one upon another, said bulkheads forming between them a compartment, and 80 foldable hinged boards in said compartment between the bulkheads and the center door ways of the car forming an insulation wall, and means for elevating and holding suspended said foldable boards, as 85 described. 90

4. A railroad car having its walls composed of horizontal boards spaced apart from each other to form between them ventilating openings, and other boards hinged 95 to the first named boards to swing into and out of position between adjacent of the first named boards to convert the car into an open or closed car, all the said boards having their edges beveled. 100

In testimony whereof I affix my signature.

EARLING A. STEINER.
